CLAIM

The ornamental design for an inflatable dock as shown and described.

DESCRIPTION

FIG. 1 is a top perspective view of the inflatable dock showing the new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top view thereof;

FIG. 7 is a bottom view thereof; and,

FIG. 8 is a bottom perspective view thereof.

The broken lines in the drawings illustrate portions of the inflatable dock that form no part of the claimed design.
